UNITED STATES PATENT OFFICE

FRANCIS HECTOR CLERGUE, OF MONTREAL, QUEBEC, CANADA

MOORING FOR AIRSHIPS

Application filed May 28, 1928. Serial No. 281,068.

My invention relates to moorings for airships, and is intended for use primarily in conjunction with mooring masts or like structures to which airships may be made fast and about which the craft is free to swing so that its nose will keep pointing into the wind. The object of my invention is to provide a cradle structure or support movable (preferably upon circular rails) about the mast or other point to which the aircraft is moored, so that the ship will be preserved from damage due to contact with the ground or to any wind force from any direction. In the preferred form of my invention, the cradle and rail trolleys prevent not only downward movement of the ship, but upward and sidewise movement as well.

Without desiring to restrict myself to the specific details illustrated, I will now proceed to describe a satisfactory and preferred form of my invention, with reference to the accompanying drawings, in which Fig. 1 is a plan view of a mooring and supporting arrangement embodying my invention; Figs. 2 and 3 are vertical sections on the lines 2-2 and 3-3 respectively of Fig. 1; Fig. 4 is a partial cross section, substantially on the line 4-4 of Fig. 3; Fig. 5 is a detail elevation of a portion of the circular track along which the cradle is movable; Fig. 6 is a vertical section on the line 6-6 of Fig. 5; and Fig. 7 is a plan view of a pneumatic cushion forming part of the cradle.

M designates a mooring mast of any well known or approved construction, generally made with a rotating upper portion M' to which the nose Y' of the aircraft Y is adapted to be made fast, such portion M' being swiveled to swing about the vertical axis of the mast. Concentrically with the mast I provide one or more cradle and trolley tracks, the example illustrated showing an inner track T and an outer track T', the distance between the tracks being equal to the radius of the inner track and being about one third of the length of the airship to be moored. Thus, for an airship 600 feet long, the inner track T would be 200 feet from the mast M, while the outer track T' would have a radius of 400 feet. But these circular tracks may

be spaced apart any distances best suited to the framing of the airship's structure.

The preferred track construction is as follows: At suitable intervals piers P of concrete or other suitable material are built in the ground G, and through such piers extend vertical rods R on which are fitted clamps C adapted to be forced down by nuts N into tight engagement with one of the outside base flanges of an I-beam I forming one of the rails of the track. The other inner base flange of said I-beam is adapted to be held down by a clamp C' pivoted at C'' to a housing H secured to the pier P by tie rods R'. I prefer to have clamps C on every pier, and clamps C' on every other pier. The clamp C' is adapted to be brought into active position by a wedge member W engaging a corresponding surface on said clamp and movable lengthwise on a rod A connected with the housing H. A nut or handwheel N', screwing on a threaded portion of said rod A, serves to hold or release the wedge or holding member W and the clamp C'. In order to facilitate removal and replacement of the beam I, the rod A, with the clamp mechanism W, N' thereon, is mounted to swing on the housing H about a horizontal axis A' ranging lengthwise of the track, and as the clamp proper C' is movable about the axis C'' (which is parallel to A'), the entire clamping mechanism may be swung aside into a recess P' of the pier P, as indicated by dotted lines in Fig. 6. The beam I may then be removed readily, after loosening the clamp C. The pier and clamp construction described is used alike for each of the rails. Fig. 5 shows an expansion joint at the adjacent ends of beam sections I of the same rail. This joint consists of a fish plate F having longitudinal slots F' through which extend the shanks of bolts B carried by the end portions of the said beams I; nuts and washers of the well-known type are fitted on said bolts, as indicated at B'.

The upper flanges of the I-beams constitute the tracks proper for the cradles. There is an outer cradle traveling on the outer track T', and an inner cradle traveling on the track T. As these cradles are substantially alike,

it will suffice to describe one of them in detail. The cradle comprises four trucks or trolleys D each having four upper rollers E and four lower rollers G rotatable about transverse horizontal axes E' and G' respectively. The upper flanges of the track beam I fit between the upper rollers E and the lower rollers G, while the frame or body of the trolley is of inverted U-shape and straddles the upper portion of the rail or beam I; thus the trolley is held against any substantial lateral movement as well as against any substantial upward or downward movement. The several trolleys belonging to the same cradle are connected rigidly by a suitable frame X, the central portion of which is preferably made with a platform J to accommodate a motor truck bringing supplies, mail, etc. for the airship, and on said platform I should also locate the controls of the adjusting mechanism to be described presently. Of course the several trolleys would be set at an angle to each other (in plan view), corresponding to the curvature of the track on which they run.

At the central portion, that is, above the platform J, is located the cradle proper consisting of a cushion K adapted to engage the hull of the airship C, a vertically movable carrier L for said cushion, and suitable mechanism for raising or lowering such carrier with the cushion. The cushion may be made of rubberized fabric, and is preferably of cellular structure. If desired, provision may be made for inflating the cushion with an air pump, after the fashion of a pneumatic tire. O indicates an inflating valve applied to a tube Q provided with separate check valves Q' controlling connections to the individual compartments or cells K'. The cushion illustrated is formed with an opening or clearance K'' for the passage of a stairway J' leading up from the platform J, to give access to the interior of the hull 45 through an opening C''. The upper surface of the cushion K is concaved to fit, approximately, the shape of the hull.

The cushion K and its carrier L may be adjusted up and down by mechanism operated from the platform J. Any suitable mechanical device (such as racks and pinions) or pneumatic or hydraulic controls may be employed. I have indicated hydraulic mechanism comprising a pump S driven by a motor U (for instance, an internal combustion engine) and having pipe connections S' to hydraulic cylinders S'' in which are fitted the vertically movable pistons or rams L' extending downwardly from the carrier L. Oil is preferred as the liquid of this hydraulic system.

The lateral or outrigger portions X' of the cradle frame X, which like the cradle frame, are supported by over and underslung trolleys, are connected with the lower ends of

steadyng cables or stays V diverging upwardly, transversely of the airship and longitudinally of the track, and the upper ends of these stays are connected with the hull at different levels, as shown. Similarly, I prefer to provide stays W diverging upwardly to connect with the aircraft body at different points of its length. It will be obvious that these cables or stays V, W should be detachable at least at one end, either at the ship or at the cradle frame.

It will be noted that the track rails project above the ground and are easily cleared of snow, mud, etc. At suitable points I would arrange level crossings Z, which would also enable supply trucks, mail trucks, etc. to reach the clear space between the rails of the same track, which space would be made wide enough (say, twelve feet) for trucks to travel readily between the rails of the same track T or T'. Inasmuch as the two cradles are independent of each other, they will adjust themselves properly to the respective portions of the airship.

I claim:

1. In an air craft mooring device of the type which includes a central mooring structure, and a track concentric with such structure, the combination of a cradle movable along said track, and a non-oscillating seating surface on said cradle conforming approximately to the shape of the hull of the air craft and adapted to directly engage only a restricted arc of the lower surface of said hull from below to provide a movable rest therefor.

2. In an air craft mooring device of the type which includes a mooring structure, and a track curved about said structure as a centre, the combination of a carriage movable along said track, a cradle adjustable in vertical directions on said carriage to different fixed positions and a non-oscillating seating surface conforming approximately to the shape of the hull of said air craft and adapted to engage only a restricted arc of the lower surface of the said hull from below to provide a movable rest therefor.

3. A support for air craft, comprising a carriage and a cradle mounted on said carriage and adjustable up and down relatively thereto to different fixed positions, said cradle having a non-oscillating seating surface concaved to conform approximately to the form of the hull of said air craft and adapted to engage only a restricted arc of the lower surface of said hull from below to provide a movable rest therefor.

4. A support according to claim 3, in which the cradle is provided with a non-oscillating cushion shaped and dimensioned to fit the hull of the air craft at a predetermined point and adapted to engage only a restricted arc of the lower surface of said hull from below to provide a movable rest therefor.

5. In a mooring device for air craft including an inflatable hull, a carriage, a cradle adjustable up and down on the central portion of said carriage to different fixed positions, 5 said cradle having a non-oscillating seating surface conforming approximately to the shape of said hull and adapted to engage only the central bottom portion of the same from below to provide a movable direct rest for said hull, and stays connected with said carriage for securing said hull in said cradle.

10 6. In a mooring device for air craft including an inflatable hull, a carriage provided with a cushion having a non-oscillating seating surface conforming approximately to the shape of said hull and adapted to directly engage only the central bottom portion of the same from below, and stays for securing said hull to the carriage to maintain the hull on 20 said seating surface.

7. In a mooring device for air craft including an inflatable hull, a carriage provided with a support having a non-oscillating seating surface conforming approximately to 25 the shape of said hull and adapted to directly engage only the central bottom portion of the same from below, and stays for securing said hull on said seating surface.

30 In testimony whereof I have hereunto set my hand.

FRANCIS HECTOR CLERGUE.
